BUTTON FEEDING MECHANISM

Abraham Bellow and Arthur Francis Carter,
Leeds, EnglandApplication January 26, 1948, Serial No. 4,436
In Great Britain October 8, 1946Section 1, Public Law 690, August 8, 1946
Patent expires October 8, 1966

3 Claims. (Cl. 112—113)

1

This invention relates to apparatus for use in connection with machines for sewing on buttons, such machines as are used in the clothing and allied trades for sewing buttons on to garments and the like.

The present practice is to first thread a plurality of buttons on to rigid wire holders from which they are passed by means of an arm to their correct position beneath the needle of the sewing machine and upon the garment placed therein. With such arrangements it has been found difficult to maintain a constant feed from the wire holders, owing to their liability to bending or distortion with the result that the buttons tend to foul on the wires.

The object of the present invention is to provide a new or improved construction of apparatus for feeding the buttons from a bulk source, such as a hopper or the like, to the sewing machine whereby the use of wire holders is eliminated.

According to the invention the apparatus comprises a chute along which the buttons are passed from a hopper or the like on to a carrier which is adapted to transfer them one at a time to the material beneath the sewing machine needle. The buttons will be controlled during their passage from the chute on to the carrier by means of a spiked roller adapted to be rotated at a controlled speed and whilst they are on said spiked roller, the buttons will be correctly positioned so that they are placed on the carrier to arrive beneath the sewing machine needle with their holes correctly aligned.

The spiked roller will be adapted to align the buttons and means associated with said roller will be provided to hold the buttons on the roller and permit the buttons to fall in succession upon the carrier which transfers each button to the sewing machine.

The buttons will travel in single file along the chute from the hopper and will be placed upon or transferred to the spiked roller face downwards, the rotation of the roller turning the buttons over so that they arrive on the carrier face upwards in correct position for sewing when the carrier transfers them to the sewing machine.

The spiked roller and the carrier will be driven from a suitably placed electric motor adapted to drive them through gearing which ensures correct timing and sequence of operation. The spiked roller may be driven intermittently through any suitable mechanism, such as a "Geneva" motion or its equivalent. Suitable controlling means will be provided, and the

2

feeding mechanism will be provided with emergency stops for use in the event of stoppage or delay arising in connection with the operation of the sewing machine.

5 In order that the invention may be clearly understood and readily carried into effect, the same will now be more fully described with reference to and by the aid of the accompanying drawings, in which:

10 Figure 1 is a part sectional side elevation of apparatus constructed in accordance with the invention.

Figure 2 is a plan view of the chute and roller shown in Figure 1.

15 Figure 3 is a fragmentary plan view showing the mounting of the spiked roller.

Figure 4 is a front view of Figure 3.

Referring to the drawings, the apparatus comprises a hopper 1 to contain the buttons which 20 are to be passed to a sewing machine (not shown) for sewing to garments or the like. An inclined chute 2 leads from the hopper 1 along which chute the buttons 3 pass face downwards.

From the lower end of the chute 2 the buttons 3 are taken up one at a time on a transfer 25 roller 4 having a number of radial spikes 5, centrally positioned on the periphery of the roller and equally spaced around it in such manner that a spike 5 passes through one of the holes

30 in the button 3. The transfer roller 4 is rotated in the direction of travel of the buttons along the chute 2, and as the spike 5 which has just taken up a button commences to approach a horizontal position, gravity causes the button to

35 pivot on the spike 5 until the button 3 is positioned with a pair of holes in axial alignment with the chute 2. When it is so positioned the further rotation of the roller 4 causes the button 3 to engage a spring guard 6 which partly

40 surrounds the roller 4 and holds the button to retain it in correct position and prevent it from falling off the spike 5 until required to do so. The roller 4 by further rotation carries the button round until it is face side uppermost, and

45 at this point, i. e. with the spike 5 pointing vertically downwards, the guard 6 is caused to release the button by the push rod 7 engaging the end of the guard 6 and causing it to release the button which falls on to the carrier 10 on the end of a

50 pivotal or swinging arm 8 adapted to transport the button to the sewing machine (not shown). The guard 6 is in the form of a cover plate of springy or resilient nature partially surrounding the roller 4, and the guard 6 terminates at 55 the point where the button is released to fall

on the carrier and is slotted at 9 for the passage of the spikes 5 of the roller 4. The mechanism for transporting the buttons to the sewing machine comprises an arm 8 provided with a plate 10 carrying fixed pins 11, the latter being positioned on the plate 10 to correspond exactly with the spacing of the holes in the buttons being used, and one of said pins 11 will align with the spikes 5 on the roller 4 when each spike is pointing vertically downwards and a button is leaving the roller to be taken by the carrier to the sewing machine.

The apparatus will be driven by suitable well known mechanism, such as an electric motor (not shown) and intermediate shafts and gearing, diagrammatically indicated as a vertical shaft 12, gearing 13, an eccentric 14, connecting rod 15 and intermittent motion mechanism 16, which latter rotates the roller 4. The shaft 12 will also actuate the push rod 7 and operate the hopper 1 which feeds the buttons face downwards to the chute 2. Instead of having a single hopper, a series of hoppers may be provided having chutes leading to a controlling and distributing mechanism for dealing with buttons of different colours or sizes before passing them to the positioning and transferring mechanism.

Means (not shown) may be provided in the chute for stopping the flow of buttons from the main hopper, in order that alternate or different buttons may be admitted to the chute from side chutes which enter the main chute adjacent the stopping means, which is preferably placed toward the lower delivery end of the main chute.

We claim:

1. In combination with a machine for securing buttons on garments, a hopper, a downwardly inclined chute leading from the hopper, an automatic button positioning transfer mechanism associated with the machine and including a rotary roller at the delivery end of the chute, said roller having circumferentially spaced radial spikes arranged to be sequentially moved past the delivery end of the chute to engage an opening in a button as the latter discharges from the delivery end of the chute, resilient means engaging each

5

button carried by a spike on the roller until the spike moves downwardly to a substantially vertical position, and means for releasing the resilient means from the button when the spike reaches its downward vertical position.

2. In combination with a machine for securing buttons on garments, a hopper, a downwardly inclined chute leading from the hopper, an automatic button positioning transfer mechanism associated with the machine and including a rotary roller at the delivery end of the chute, said roller having circumferentially spaced centrally disposed radial spikes arranged to be sequentially moved past the delivery end of the chute to engage an opening in a button as the latter discharges from the delivery end of the chute, a resilient retaining plate partly surrounding the roller and having a slot for receiving the spikes during a predetermined rotary movement of the roller, said plate engaging each button on the roller until the button moves downwardly to a position where the spike engaging the button is in a substantially vertical position, operable means when the said spike reaches the downwardly vertical position for releasing the plate from engagement with the button so as to discharge the same from the roller, and means positioned below the roller for receiving each button as it is discharged from the roller.

3. In combination with a machine for securing buttons on garments as called for in claim 2, in which means are provided for intermittently rotating the roller and for actuating said operable means.
